J. C. L. KREBS AND W. W. WELLS,
VARIABLE SPEED GOVERNOR CONTROL,
APPLICATION FILED NOV. 18, 1918.

1,324,198.

Patented Dec. 9, 1919.

UNITED STATES PATENT OFFICE.

JOHN C. L. KREBS AND WALTER W. WELLS, OF CLYDE, OHIO.

VARIABLE-SPEED-GOVERNOR CONTROL.

1,324,198.

Specification of Letters Patent.

Patented Dec. 9, 1919.

Application filed November 18, 1918. Serial No. 263,060.

To all whom it may concern:

Be it known that we, JOHN C. L. KREBS and WALTER W. WELLS, citizens of the United States, and residents of Clyde, in the county of Sandusky and State of Ohio, have invented a certain new and useful Variable-Speed-Governor Control; and we do hereby declare the following to be a full, clear, and exact description of the invention, such as will enable others skilled in the art to which it appertains to make and use the same, reference being had to the accompanying drawings, and to the characters of reference marked thereon, which form a part of this specification.

This invention relates to variable speed governors of the centrifugal type, and particularly to control means therefor operable to control the speed of running of the associated engine.

The object of this invention is the provision of a simple and efficient control means for the throttle governors of steam, gas, gasoline, oil, or other engines, which means is capable of easy and quick adjustment to render the governor active to close the throttle at the speed desired, and which is also capable of accurately controlling the engine at low speeds as well as at high speeds.

In the use of governors of this class, it must be borne in mind that since centrifugal force varies with the square of the R. P. M., the forces exerted by the governor weights are very much greater at high speed than at low speed, and consequently the increase in these forces, as the weights move from inner to outer position, is correspondingly greater. Accordingly, the spring which is employed to resist the outward movements of the governor weights must be so designed as to balance the centrifugal forces under all conditions. This was accomplished in an earlier invention described and claimed in Patent No. 1,117,759, dated November 17, 1914, by so changing the position or relation of the spring with respect to the weights that the leverage with which it acted on the weights was greater at high speeds. In the present instance, the relation of the spring to the governor weights remains the same, but the spring is designed so that its stiffness may be adjusted by changing the effective length thereof.

The invention is fully described in the following specification, and while, in its

broader aspect, it is capable of embodiment in numerous forms, a preferred embodiment thereof is illustrated in the accompanying drawings, in which,

Figure 1 is a sectional view of a governor equipped with our invention, with the control parts in high speed position. Fig. 2 is a plan of an engine of the internal combustion type equipped with the invention, 65 and Fig. 3 is a section of an automobile steering wheel with the governor control parts associated therewith.

Referring to the drawings, 1 designates the governor shaft, which, in the present instance, is shown as being geared, or otherwise suitably connected, to the crank shaft of an associated engine 2. 3 designates the governor weights which are pivotally carried by arms 4, fixedly projecting from opposite sides of the shaft 1, whereby the weights are permitted to have swinging movements in planes which are longitudinal to the shaft, as is well understood in the art. The weights 3 have arms 4 projecting 80 inwardly from their inner ends toward the shaft 1 for contact with an end of a sleeve 6 that is mounted for free sliding movements on the shaft 1. The contact of the sleeve 6 with the weight arms 5 is such, in the present instance, that an outward movement of the weights will cause the sleeve to have movement to the right on the shaft 1.

The governor housing is designated 7, and mounted in suitable bearings in this housing transverse to the shaft 1 adjacent to the outer end of the sleeve 6, is a rocker-shaft 8 having an arm 9 projecting upward therefrom in contact with the outer end of said sleeve. The arm 9 is preferably forked to 95 adapt it to straddle the shaft 1. The rock shaft 8 has another arm 10 projecting therefrom at an angle to the arm 9 and co-operating with said first arm to form a bell crank lever, and the outer end of the arm 14 is 100 connected by a link 11 to the free end of a spring 12.

The spring 12 is of multiple leaf bar form and has the end thereof opposed to the one to which the link is attached fixed to a re-entrant portion 7^a of the housing 7, in the present instance, by a screw 13, the spring being substantially parallel to the shaft 1 and its mounting being such as to permit its flexing movements to be toward and away from said shaft. It is evident that an outward movement of the sleeve 6 occasioned by

an outward or centrifugal movement of the 5 governor weights 3 will, in the present instance, rock the shaft 8 in clockwise direction and communicate a flexing movement to the attached end of the shaft 12 in an outward direction with respect to the governor shaft.

The shaft 8 is connected in a suitable manner to a throttle valve 14, which valve, in 10 the present instance, if the engine is of the internal combustion type, comprises a part of an associated carburetor 15, as shown in Fig. 2. A rotation of the shaft 8, occasioned by an outward movement of the sleeve 6, is 15 intended to impart a closing movement to the throttle valve, thereby limiting the flow of operating fluid to the engine cylinders.

In order to change the effective length of the spring 12, whereby to change its flexibility or stiffness, it is necessary to shorten 20 or lengthen the effective portion of the spring. This is accomplished by providing a shiftable spring supporting or bearing part 16 at the outer side of the spring, which 25 may be termed a carriage, being mounted for shifting movements lengthwise of the spring within the base portion of the housing 7. The carriage 16 is provided with opposing rollers or anti-friction members 17, 30 one of which has rolling contact with the outer side of the spring 12, while the other has rolling contact with the part of the housing 7 against which it is intended to bear.

It is evident that an outward movement 35 of the carriage 16 from the dotted line position shown in Fig. 1 will shorten the effective length of the spring 12, proportionally increasing the stiffness thereof, thereby causing the spring to offer a greater resistance to an outward movement of the sleeve 6 of the governor. In other words, it will 40 be understood that with the other dimensions of the spring remaining constant, the flexibility thereof increases with its length, 45 so that if the carriage 16 is in the full line position shown in Fig. 1, the spring is of greater stiffness, and a much greater speed of rotation of the shaft 1 will be required to close the throttle valve 14 against the tension of the spring than would be required 50 if the carriage were in the dotted line position shown in said figure.

The carriage 16 has a rod 18 projecting therefrom lengthwise of its intended plane 55 of movement through a bearing provided therefor in the housing 7, and has connection at its outer end with any suitable control mechanism. In order that the movement of the carriage 16 may be controlled 60 by the driver of an automobile without leaving his seat in the automobile, a simple mechanism is illustrated for such purpose. This mechanism comprises a set of bevel gears 19, which are disposed at the lower end 65 of the steering wheel column, one bevel gear

having an arm 20 projecting radially therefrom and connected to the outer end of the rod 18 through the medium of a link 21, and the other bevel gear being fixed to the lower end of a shaft 22 that is mounted for rotary 70 movements in the steering shaft 23, to which the hand steering wheel 24 is attached. The shaft 22 extends without the upper end of the steering shaft 23 and is provided at such end with a control arm 25. A lever member 75 26 is fulcrumed to the arm 25 and has its inner end attached to the upper end of a rod 27, which extends down through the shaft 22 and attaches at its lower end to a latch-lever 28 which is fulcrumed to the outer end 80 portion of the bevel gear 19 attached to the shaft 22. The free end of the latch lever 28 is adapted to engage within any one of a series of notches on a segmental rack 29, which is fixed to a stationary part of the 85 steering column.

It will be understood in the operation of our invention that by moving the carriage or spring support 16 to the right from the dotted line position shown, the effective 90 length of the spring 12 is shortened and it becomes stiff enough to balance the large increase of centrifugal force of the governor weights as they move out when revolving at high speed. Moving the carriage to the left 95 from the full line position, lengthens the effective portion of the spring and makes it so flexible that the small increase of centrifugal force, due to the governor weights moving out when running at low speed, is 100 able to move the rock shaft 8 through its entire range of movement.

We wish it understood that our invention is not limited to any specific construction, arrangement or form of the parts, as it is 105 capable of numerous modifications and changes without departing from the spirit of the claim.

Having thus described our invention, what we claim as new, and desire to secure 110 by Letters Patent, is,—

In a governor, a housing, a bar-like spring fixed at one end to the housing and spaced from the adjacent wall thereof for flexing toward and away therefrom, a governor 115 shaft journaled in the housing, a centrifugal governor carried by the shaft, means connected to the free end of the spring and operable by the centrifugal governor for flexing the spring, and an adjustable spring 120 bearing member having a part slidable on said housing wall between the latter and the spring and having a second part slidably engaging the spring at varying points along the latter for varying the length of the effective portion of said spring.

In testimony whereof we have hereunto signed our names to this specification.

JOHN C. L. KREBS.
WALTER W. WELLS.
